HARNESS CORD

Warren B. Harris, Millbury, Mass.

Application January 7, 1939, Serial No. 249,794

7 Claims. (Cl. 24—123)

This invention relates to harness cords for looms, and more particularly to the construction of the end of the harness cord, which comprises an eyelet adapted to be connected to other parts of a loom mechanism.

In my prior Patent No. 1,720,272 I have shown a harness cord comprising a textile cord of braided thread reinforced by a central flexible wire core, and in which this wire core is looped around an eyelet and then twisted about itself and held in place by a metal ferrule. Construction of this and other types present certain disadvantages owing particularly to the cost of manufacture and to the difficulty of providing a satisfactory eyelet and a suitable connection with the cord. Any breakage of the harness cord is likely to cause injury to the cloth being woven, and it is particularly desirable that the eyelet be made of durable material which will give a long life of useful service and that it be secured to the cord so strongly that the connection cannot break away.

The primary object of this invention is to overcome the problems in such prior art constructions and to provide a harness cord having the eyelet at its end made of suitable material which is highly resistant to wear and which is so fastened in place that it will not become loose or permit breakage of the cord at the junction.

A further object is to provide a very simple construction which may be readily and economically manufactured and which will give a long life of useful service. Further objects will be apparent in the following disclosure.

Referring to the drawing, I have there shown various embodiments of this invention wherein:

Fig. 1 is a perspective view, partly broken away, of a complete harness cord;

Fig. 2 is a view taken at right angles to Fig. 1, showing one end of the cord looking in the direction of the arrow 2 of Fig. 1;

Fig. 3 is a sectional view of one end of the cord of Figs. 1 and 2;

Fig. 4 is a further sectional view on the line 4—4 of Fig. 3;

Figs. 5, 6 and 7 are sectional views showing three modifications;

Fig. 8 is a sectional view taken on the line 8—8 of Fig. 7; and

Fig. 9 is a fragmentary sectional view of a further modification.

This harness cord is used in a loom to operate the harness frame that control the warp thread, but it may be used in connection with other

mechanisms employed in the loom. The cord comprises a flexible twisted wire 10 covered over by and reinforcing an outer sheath 12 of braided thread or other suitable material, which covering serves particularly to prevent undue wear of the pulley over which the cord runs. In accordance with my invention, I have provided an eyelet which is adapted to receive the linkage connection, and this eyelet is in turn connected to the central reinforcing wire 10. The end of the reinforcing wire and the end of the fabric covering 12 thereover are all connected together by molding a suitable substance thereabouts so as to make a rigid and permanent union of these parts.

In the form shown in Figs. 1 to 4 inclusive, the eyelet 20 is made of a piece of formed steel wire or other suitable material which is forged or otherwise shaped, as in a wire forming machine, to provide a loop 22 adapted to be connected to other linkage mechanism. This piece of wire 20 is preferably bent to form a substantially circular arcuate portion to receive the connecting linkage, and to provide a wedge shaped throat within which the free end of the wire 10 is wedgedly secured. This is accomplished by bending the two ends 23 and 24 of the wire towards each other as illustrated. The end 23 is short, while the end 24 is longer and bent at right angles to form a part 25 which serves to close the end of the wedge or V-shaped throat. After the fabric covering 12 over the end of the wire 10 has been stripped back, then the free end of the wire is inserted into that wedge shaped throat and is bent over the laterally projecting arm 25, as shown in Figs. 3 and 4. The loose and frayed ends of the wire 10 will ordinarily spread apart and hold the wire firmly in place. These parts are, however, secured firmly and permanently in position by die casting a metal, such as a suitable "Babbitt" alloy, in position around all of these projecting parts, as shown particularly in Figs. 3 and 4. This die cast metal not only embeds the frayed ends of the braided fabric 12, but it also interlocks with and embeds the frayed ends of the wire strands 10 and passes into the eyelet 22 and thus holds all of these parts securely in place and prevents any relative movement thereof. This Babbitt metal also serves to make the end of the cord more attractive and to cover up any loose or frayed ends.

A modification is shown in Fig. 5, in which the free end of the wire 10 is bent around to form the loop 30, and the outer end of the wire 32 is bent back into a position close to the main

portion of the wire. Then, when the metal 34 is die cast in place around the end of the braided cord 12, as well as around the wire portions 10 and 32, it will thus form an eyelet having the die cast metal itself entirely encasing and embedding the end of the wire 10. The die cast metal may cover the wire loop 30 as illustrated, or it may leave the loop exposed. In this construction the amount of die cast metal within the eyelet may be proportioned as desired, but the main strength and wear resistance of the eyelet will be found in the bent wire 10.

If it is desired to further increase the wear resistance of the eyelet, I may use the construction shown in Fig. 6, wherein the wire 10 has its outer free end threaded into a steel or other metal sleeve 36 which is of sufficient size and length as illustrated to form the eyelet when bent back upon itself. The wire may make a fairly snug fit within the sleeve and the wire itself has sufficient resistance to bending so that it will not drag easily out of the sleeve when subjected to a tensional force. But the metal 38 die cast around the wire 10 and the two ends 20 of the sleeve 36 will serve to hold all of the parts rigidly in position. If desired, the wire 10 may be threaded through the sleeve 36 far enough so that some of its outer frayed end will project into the Babbitt metal 38 and thus aid in locking the wire rigidly in position and preventing it pulling back through the sleeve.

In the construction shown in Figs. 7 and 8, I have used a separate ring shaped eyelet around which the wire 10 is secured. This iron or steel ring 40 may be U-shaped in section and have its two ends open, so that the wire 10 may be passed around it within the U-shaped channel. The outer free end of the wire 10 is positioned close to the main strand of the wire 10, so that when the metal 42 is die cast around these parts, as shown in Fig. 7, the wire 10 will be held rigidly in place. The die cast metal is also preferably positioned to cover the free ends of the eyelet and thus wedge into the V-shaped 45 part and lock the ends of the eyelet in position. The eyelet is so shaped, as shown in the drawing, that a link connected to the harness cord will impose its wear solely on the metal of the eyelet and will not touch the end of the cord 10. The casing of die cast metal may in each 50 one of these modifications be permitted to cover the eyelet as well, but of course leave a central hole therethrough for attaching to the linkagé, in which case the die cast metal will add somewhat to the wear resistance of the harness cord.

It will now be appreciated that in each of these constructions I have provided an eyelet which is made of a wear resistant metal, and that this eyelet is connected directly to the reinforcing wire of the harness cord. Moreover, the sheath around that reinforcing wire, the wire itself and the eyelet are all rigidly connected together by means of molded metal that embeds the adjacent portions of the same. This makes a rigid structure providing a permanent connection between an eyelet and the harness cord. This die cast covering is located only on the end of the cord, and it does not interfere in any way with the flexibility of the cord or its use in a loom. The cord itself presents a textile surface which will not wear materially the pulley over which it runs, and yet the main strength of the cord is found in the reinforcing wire therein. Owing 70 to the use of the die cast metal, I provide mate-

rial advantages over a separate ferrule or sleeve placed over the ends of the cord and crimped in place. Such a ferrule does not add much strength to the construction and is mainly used to cover up the loose ends of the various parts; whereas in the present case, the die cast metal that has been forced into position around all of the parts will aid materially in strengthening the device. There will, therefore, be no danger of the harness cord breaking at the connection except as the eyelet ultimately wears out. The connection between the eyelet and the cord will be a permanent one, otherwise.

For certain types of construction it is not necessary that the eyelet be connected directly to the wire 10, but it may be connected indirectly thereto by means of a molded substance, such as die cast metal. This is illustrated in Fig. 9, in which the reinforcing wire strands 10 terminate short of the eyelet and the wire 20 and the fabric covering 12 are connected to an eyelet 44 solely by the die cast or molded material. The eyelet may be of various shapes which will serve to form a loop or a hooked end for connecting with other linkages, and which will interlock rigidly with the molded connecting portion. This may be accomplished by making the eyelet of a substantially U-shape having its two legs 45 bent at their ends 46 to form locking lugs or hooks each of which extends in a direction at an angle to the line of tensional force applied to the cord. The substance 47 which is molded or die cast around the free end 10 of the wire, and preferably around the end of the fabric covering 12, embeds and unites firmly with these parts and it interlocks with the hooked ends 46 of the eyelet. It will be appreciated that the strands at the end of the wire 10 may be frayed out or tired in a knot or otherwise shaped or enlarged 40 to form a very strong union with the molded substance 47. The molded substance 47 may surround the eyelet, and the latter may serve as a reinforcement therefor. If the eyelet is sufficiently wear resistant, it may be exposed and 45 not coated with the molded substance at the outer point where it fastens to the cord adjustment end or a hook fastened into the harness frame of the loom. Numerous other modifications will now be apparent to one skilled in this 50 art.

It will also be appreciated that the term "eyelet" as used herein is to be interpreted broadly as covering either a closed ring or a U-shaped or S-shaped member or any other suitable shape 55 of metal or other wear resistant material which may be interlocked with the molded substance employed to unite the eyelet with the main body of the cord. This eyelet may, for example, be shaped as a hook with its embedded end serrated or screw threaded or provided with locking flanges or lugs, or it may have a bent or outwardly turned end or any other suitable shape which suitably interlocks with the molded body. Each of the modifications shown in the 60 drawing may be suitably varied in the light of the above disclosure. For example, the wire 10 shown in Fig. 4 may be wound around the cross bar 25 to aid further in locking the parts in place and the free end may be either wedged 70 into the V-shaped slot of the eyelet or not, as desired. Likewise, the ring shaped eyelet, shown in Figs. 7 and 8, may have any shape or arrangement about which the wire end 10 may be secured.

The molded material exemplified above by a die cast metal may also be any suitable molded substance, such as a resinoid which is capable of uniting the eyelet and the cord end. Such 5 a resinoid may be of the type of the "Bakelite" phenol-formaldehyde moldable substance or of the type of the "Glyptal" phthalic-glycerol resin, or of the type of the "Tenite" cellulose acetate resin, and various other substances will 10 likewise be usable for this purpose. In every case, it is desirable that this intermediate molded body connect an eyelet of suitable shape and form with the end of the wire in the textile cord, and preferably also with the textile covering 15 of that wire. Hence, in each of the above described constructions, various suitable resinoids may be substituted for the die cast metal. This resinoid may be molded in accordance with standard practice. For example, a powdered 20 "Bakelite" resinoid in a potentially reactive condition or "Tenite" cellulose acetate may be placed in the mold in suitable quantity after the eyelet and cord have been properly located and then subjected to heat and pressure in accordance 25 with standard practice.

It will now be appreciated that various other modifications may be made in this construction within the scope of my invention, and that the above description is meant to be illustrative of 30 the general principles and certain specific applications of the invention without limiting the claims to the forms shown in the drawing. Each of the modifications illustrated comprises an eyelet, whether a separate member or formed by 35 looping the end of the wire, and this eyelet is secured in place, and made integral with the reinforcing wire, by a substance molded, as by die casting, over the parts to be interlocked. This molded casing preferably covers the end of the 40 sheath and thus connects the eyelet directly with the sheath 12 and so adds further strength to the cord, as well as serving to seal the parts and preventing the entrance of moisture to the wire. The claims are therefore to be interpreted as covering 45 such equivalent constructions as embody these features.

I claim:

1. A harness cord comprising a flexible sheath, a reinforcing wire within the cord and projecting from the sheath, a metal part forming an 50 external eyelet which is connected to the wire within the sheath and transmits a tensional force thereto, and a molded body embedding the ends of the wire and sheath and a part of the eyelet 55 which secures the parts rigidly positioned.

2. A harness cord comprising a flexible wire, a metallic terminal eyelet forming an end of the cord which is so shaped and arranged that it interlocks with the wire, and a molded body embedding the wire end and the adjacent portion 5 of the eyelet which secures the parts rigidly positioned.

3. A harness cord comprising a covering of textile material, a central reinforcement wire therein and projecting from one end, an eyelet formed 10 of the projecting wire end and a molded body which is intimately associated with and embeds the free end of the wire and seals the end of the covering and holds the parts rigidly in position. 15

4. A harness cord comprising a covering of textile fabric, a central reinforcement wire therein, a metal eyelet shaped to provide a wear resistant member about which the reinforcing wire is looped and which solely receives the wear from 20 a connecting link, and a molded body intimately associated with and embedding the outer end of the wire which serves to hold the wire secured in position around the eyelet.

5. A harness cord comprising a covering of 25 textile fabric, a central flexible reinforcement wire projecting from one end thereof, a metal eyelet having a wedge shaped slot, the end of the wire being located in the slot, and a molded body intimately associated with and embedding 30 a portion of the eyelet and the end of the wire which secures the eyelet in position.

6. A harness cord comprising a covering of textile fabric, a central flexible reinforcement wire projecting from one end thereof, a metal 35 eyelet shaped to provide a loop at one end for a linkage and a wedge shaped slot at the opposite end, the free end of the reinforcement wire being located in the wedge shaped slot, and a molded body embedding the ends of the strands 40 of the textile fabric and the reinforcing wire and interlocking with the wedge shaped slotted end of the eyelet so as to hold the parts connected together.

7. A harness cord comprising a covering of 45 textile fabric, a flexible reinforcement wire within and projecting therefrom, a metal eyelet having two free ends shaped to form a V-shaped slot and provide a cross bar, the free end of the wire being wedged in the slot and passing over the bar 50 and a molded body embedding the wire and interlocking with the cross bar of the eyelet which serves to secure the parts together.

WARREN B. HARRIS. 55
